UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

CHAIN GRATE STOKER

Application filed May 4, 1928. Serial No. 275,009.

This invention relates to a furnace that is provided with a chain grate stoker operated under forced air blast in which provision is made for utilizing leakage air by conducting it to a portion of the grate and utilizing it for combustion purposes. The invention will be understood from the description in connection with the accompanying drawing in which Fig. 1 is a section through an illustrative embodiment of the invention taken along the line 1—1 of Fig. 2, and Fig. 2 is a longitudinal vertical section taken along the line 2—2 of Fig. 1. In the drawing reference character 1 indicates a furnace that is provided with a fuel hopper 2 with an opening 3 at the bottom thereof for feeding a layer of coal of proper thickness onto the upper run 4 of a chain grate. The lower run of the chain grate is indicated at 5 and the chain passes around rollers 6 and 7 at opposite ends of the stoker which may be driven in any convenient manner.

Cross members or partition plates 8 in the form of I-beams extend laterally across the stoker and in conjunction with plates 8a extending therebetween provide boxes or compartments 9, 10, 11 and 12 beneath the upper run 4 of the chain grate. Another compartment 13 is arranged alongside the compartment 12 and formed by the I-beams 8 in conjunction with a partition 8" and seals 13a and 30 located along the upper side of the lower run 5 of the chain grate. Seals 8' are provided at the upper ends of the I-beams 8 to prevent air from passing from one compartment to the other. An I-beam 13' passes longitudinally through the stoker between the upper and lower runs of the chain grate dividing the stoker into two similar parts. A series of ducts 14 and 15 are provided at the sides of the stoker and dampers 16 and 17 in these ducts, operated by handles 18 and 19, control the amount of air passing through the ducts into the respective compartments 9 to 13, by way of the openings 20 to 24 on opposite sides of the stoker which lead to the compartments 9 to 13, respectively. The plates 8a are arranged to provide V-shaped bottoms for the compartments and screw conveyors 25 are located at the bottom of the

compartments to remove the siftings that may fall through the upper run 4 of the chain grate into these compartments.

A drag plate 26 is provided below the lower run 5 of the chain grate and is supported upon I-beams 26'. A damper 27 operated by a handle 27' is provided in the floor of the compartment 12. A wall or partition 8" extends from the partition plate 8 at the right hand end of compartment 12 (Fig. 2) to the seal 30 located along the upper side of the lower run 5 of the chain grate, and a damper 28 operated by a handle 28' is provided in this wall or partition 8", to control the amount of air admitted to compartment 13 through an opening in said partition. An air tight casing 31 is provided at the front end of the stoker below the coal hopper 2.

The operation is as follows: The dampers 16 are regulated so as to have the highest pressure in the compartment 9 and lower pressures in the succeeding compartments, or the pressures in the compartments may be regulated in any other convenient manner. Air that leaks from the first compartment 75 past the links of the chain and the first seal, as indicated by the front arrow, passes to the space 32 and then to the space between the bottoms of the boxes or compartments and the drag plate of the stoker. This air 80 may be permitted to pass into the compartment 12 by opening the damper 27 or into another compartment 13 below the right hand end of the upper run of the chain grate 4 by opening the damper 28, or both, so that 85 air that has leaked from the first compartment passes through the fuel bed where the fuel has become thin due to combustion. The siftings that fall through the upper run of the chain grate near its rear end are 90 carried by the lower run of the grate along the drag plate 26 and discharged into the opening provided for the siftings at the left hand end of this drag plate.

Air is usually heated before it is fed to a 95 stoker for combustion purposes, and if leakage air is not recovered in some such way as described above, the heat would be wasted so that a decided economy is effected by this invention. Leakage from the front compart- 100

ment would ordinarily pass to waste outside of the furnace and as this pressure is in most instances higher than at some succeeding point, the leakage air can be returned by utilizing pressure differences to a compartment in which the pressure is lower.

I claim:

1. In a furnace, a chain grate stoker, a plurality of air compartments having air inlets formed beneath the upper run of said stoker, and means between the lower run of said stoker and said compartments to convey leakage air from a compartment disposed towards the forward part of said furnace to a compartment disposed towards the rear thereof.
2. In a furnace, a chain grate stoker, a plurality of air compartments having air inlets formed beneath the upper run of said stoker, means between the lower run of said stoker and said compartments to convey leakage air from a compartment disposed towards the forward part of said furnace to a compartment disposed towards the rear thereof, and means associated with said rear compartment to control the amount of leakage air admitted thereto.

3. In a furnace, a chain grate stoker having a plurality of compartments formed below and opening through the upper run thereof, means for supplying air under different pressures to different compartments, and means for conducting leakage air from one compartment to another compartment under a lower pressure.

4. In a furnace, a chain grate stoker having compartments formed between the upper and lower runs thereof and opening through the upper run thereof, means for supplying air under different pressures to successive compartments of said stoker, and means for conducting leakage air from one compartment to a non-adjacent compartment under a lower pressure.

45 5. In a furnace, a chain grate stoker having compartments formed between the upper and lower runs thereof and opening through the upper run thereof, means for supplying air under different pressures to different compartments, and means for conducting leakage air from a front compartment to a rear compartment under a lower pressure.

6. In a furnace, a chain grate stoker having compartments formed between the upper and lower runs thereof and opening through the upper run thereof, means for supplying air under different pressures to different compartments, and means for conducting leakage air from a compartment adjacent the front end of said stoker longitudinally below said compartments to a compartment under a lower pressure, said means including a damper controlled air inlet to said low pressure compartment.

65 7. In a furnace, a chain grate stoker hav-

ing compartments formed between the upper and lower runs thereof and opening through the upper run thereof, means forming an air-tight chamber at the front of said stoker, means for supplying air at different pressures to different compartments of said stoker, and means for conducting air leaking into said front chamber to a rear compartment under a lower pressure.

8. In a furnace, a chain grate stoker having side-by-side compartments formed between the upper and lower runs thereof and opening through the upper run thereof, means forming an air-tight chamber in front of said compartments, a drag plate below said lower run and spaced from the bottoms of said compartments, means for supplying air under different pressures to different compartments, and means for conducting air leaking into said front chamber through the space between the bottoms of said compartments and said drag plate to a compartment under a lower pressure adjacent the rear end of said stoker.
